UNITED STATES PATENT OFFICE

119,127

DESIGN FOR A DRESS

Mark Jacobson, New York, N. Y.

Application January 24, 1940, Serial No. 89,659

Term of patent 3½ years

To all whom it may concern:

Be it known that I, Mark Jacobson, a citizen of the United States of America, residing in the city of New York, county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is a plan view of the detachable panel of the dress shown in Fig. 1.

The characteristic feature of my design resides in the combination on the specific dress disclosed of the specific detachable panel as shown.

I claim:

The ornamental design for a dress, substantially as shown and described.

MARK JACOBSON.
